UNITED STATES PATENT OFFICE.

PHILIP T. DODGE, OF NEW YORK, N. Y., ASSIGNOR TO MERGENTHALER LINOTYPE COMPANY, A CORPORATION OF NEW YORK.

TYPE BAR OR SLUG.

1,197,718.

Specification of Letters Patent. Patented Sept. 12, 1916.

Application filed June 28, 1915. Serial No. 36,639.

To all whom it may concern:

Be it known that I, PHILIP T. DODGE, a citizen of the United States, residing at New York, in the county of New York and State of New York, have invented certain new and useful Improvements in Type Bars or Slugs, of which the following is a specification, reference being had therein to the accompanying drawing.

10 My invention relates to type bars or slugs, such as linotypes, bearing on their edges the type characters to appear in print. In use, the slugs are assembled side by side in a row or column to make up the printing form, from which the print or impression is taken.

20 Certain classes of work, such as advertising, illustrative matter and the like, require the use of cuts or printing plates in the form, and to meet this requirement, the slugs are usually cut off just beyond their type characters to provide an open space in the form for the reception of a supporting block upon which the cut is mounted.

25 This practice is objectionable, as it not only involves a number of different operations which entail much labor and loss of time, but in addition difficulty is experienced in locking up the form in the proper and exact 30 manner required. Furthermore, the use of supporting blocks for the plates is undesirable, since they must be specially prepared to correspond to the particular plates to be inserted, and moreover they can rarely be 35 used after one service.

My invention is intended to overcome the above objections and aims to provide slugs with plain or smooth surfaces upon which the printing plate may be directly supported, and with upstanding lips or projections of less than type height to engage the edges of the plate and hold it securely in place. The location of the overhanging 40 projections is made to correspond to the size or extent of the plate, that is, they are located at the opposite ends of the slugs or centrally thereof according to the size or position of the plate or according to the extent of the type characters on the slugs.

45 These features and others will be more fully discussed in the detailed description to follow and finally pointed out in the claims.

In the accompanying drawing, I have shown my invention merely in preferred 50 form and by way of example, and as ap-

plied to a type bar as produced in the ordinary commercial linotype machine, but it will be understood that the invention is capable of embodiment in other forms, and of adaptation to type bars of other kinds, 60 which will still be comprised within its spirit. Generally speaking, I desire it to be understood that I do not limit myself to any specific form or embodiment, except in so far as such limitations are specified in 65 the claims.

Referring to the drawing:—Figure 1 illustrates a printing form comprising type bars or slugs constructed in accordance with my invention; and Fig. 2 is a section on the 70 line 2—2 of Fig. 1.

As shown in Fig. 1, the form A comprises the series of type bars or slugs B and the cut or plate C, the slugs having on their upper edges the usual type characters B¹, 75 and being arranged side by side in a column so as to be “locked up” in an ordinary chase, in the manner indicated, for instance, by dotted lines in Fig. 2.

As previously stated, the present invention is intended to make the underlying slugs B of such form as to afford direct support for the plate C and to hold it securely in place. To this end, the slugs are provided with flat or plain surfaces B², upon which the base of the plate may rest, these surfaces being located at such height as to support the plate with its printing face flush with the type characters B¹. Each of the slugs is also provided with a pair of complementary upstanding lips or projections B³ which are preferably undercut so as to engage and overhang the beveled edges of the printing plate, and thus to hold the latter securely against edgewise or lateral displacement. 95 These projections B³ are of less than type height so as to stand below the printing surface.

Owing to the irregular extent of the plate C, the projections B³ on the respective slugs are differently located to correspond. For instance, the projections on the slugs marked D are uniformly spaced apart on the slugs and are located well to the left thereof, while the projections on the slugs marked E are spaced apart a greater distance and are shown as occupying a substantially central position. The only requirement in this connection is that the position of the holding projections be made to correspond to the 110

extent or size of the plate employed, it being a simple matter in the production of the slugs to vary their location in the desired manner. It will further be noted that 5 most of the slugs having the holding projections B^3 are also provided with the type characters B^1 , while others are without them. It will be obvious, of course, that the presence or absence of the characters 10 will depend essentially upon the class of work involved.

In order to facilitate the insertion of the plate C in position upon the slugs, the latter may be divided into sections, as indicated in Fig. 2, wherein one of the slugs is 15 shown as comprising two sections B^4 and B^5 , each carrying one of the complementary holding projections B^3 . In this way, the plate may be laid down flatwise upon the 20 plain surfaces B^2 of the slugs and secured firmly in place by compressing the slugs endwise, as is usual in making up the form. The line of division is preferably located substantially midway between the complementary 25 holding projections B^3 , so that the plain surfaces B^2 of the two sections may be of nearly equal length and afford an extended support for the plate, whose downward pressure upon the slugs will thus act 30 to keep it properly seated and insure the engagement of the holding projections B^3 over its edges.

The foregoing will serve to illustrate the underlying principle of my invention, and 35 it will be manifest that many changes and variations therein may be made without departure from its scope. Thus the form of the holding projections may be altered or the printing slugs may be integral throughout. Further, instead of providing all of 40 the slugs which underly the plate with holding projections, a smaller number may be so formed, and this without necessarily locating two projections on each slug,—for 45 instance, the projections which engage the plate at one edge may be located on different slugs from those which engage it at the opposite edge. The essential idea is that the 50 projections be so arranged as to engage and hold the printing plate in proper position upon those slugs which give it support.

I am aware that it is old to provide a type bar or slug with a pair of projections of less than type height, but these projections are 55 not only designed for a purpose different from that described herein but are incapable of being used for a like purpose. These projections are employed to hold a straight rule in position upon the slugs, and for this 60 reason, they must be uniformly spaced apart on the different slugs and also located in the same position in the length thereof. Further, the projections are formed from a single matrix, which must not only have a 65 given dimension to insure their uniform

spacing, but which must also be set in the same position in the following lines to insure the proper alinement of the projections on the successive slugs when assembled in the form. My invention, on the other hand, dealing as it does with broad and flat plates of irregular extent, requires that the holding projections be spaced apart different distances on the successive slugs, and in addition that they be located in different 70 positions lengthwise of the slugs. These and other distinctions will be apparent to those skilled in the art.

Having thus described my invention, its construction and mode of operation, what I 80 claim and desire to secure by Letters Patent of the United States is as follows:

1. A printing form comprising a series of slugs arranged side by side, certain of the slugs having plain or flat extended surfaces 85 to receive and support a broad and flat cut or printing plate, and formed with widely separated upstanding projections to engage the plate and hold it in position thereon.

2. A printing form comprising a series of slugs arranged side by side, certain of the slugs having plain or flat surfaces to receive and support a broad and flat cut or printing plate, and formed with widely separated undercut projections to overhang 95 the edges of the plate and hold it securely in place thereon.

3. A printing form comprising a series of slugs arranged side by side, certain of the slugs having plain or flat surfaces to receive and support a cut or printing plate of irregular extent, and formed with upstanding projections to hold the plate in position, said projections being located in different positions on the respective slugs so as 100 to correspond to the irregular extent of the plate.

4. A printing form comprising a series of slugs arranged side by side, certain of the slugs having plain or flat surfaces to receive and support a cut or printing plate of irregular extent and formed with undercut projections to engage and hold the plate in position, the said projections being located in different positions on the respective slugs 105 to correspond to the irregular extent of the plate.

5. A printing form comprising a series of slugs arranged side by side, certain of the slugs having plain or flat surfaces to receive and support a cut or printing plate of irregular extent and each formed with a pair of complementary undercut holding projections between which the plate is adapted to be seated, the projections of the respective pairs being irregularly spaced to 110 correspond to the irregular extent of the printing plate.

6. A type bar divided into sections which are adapted to be arranged end to end, and 115

each formed with a plate-holding projection, for the purpose described.

7. A type bar divided into sections which are adapted to be arranged end to end, and
5 each formed with an undercut holding projection to overhang the edge of a printing plate.

8. A type bar having a flat or plain surface to receive and support a printing plate,
10 and provided at opposite ends of the sur-

face with holding projections to engage the plate, the said bar being divided into sections substantially midway between the projections, for the purpose described.

In testimony whereof, I have affixed my 15
signature in presence of two witnesses.

PHILIP T. DODGE.
